United States Patent Office

Des. 186,630
Patented Nov. 10, 1959

186,630

PAIR OF GOGGLES

Francis J. Corrigan, Kutztown, Pa., assignor, by mesne assignments, to The Electric Storage Battery Company, Philadelphia, Pa., a corporation of New Jersey

Application June 19, 1956, Serial No. 41,977

Term of patent 14 years

(Cl. D57—1)

Fig. 1.

Fig. 2.

The headband is shown broken away in Figure 2 for convenience of illustration.

The dominant feature of my design resides in the full lines shown on the drawing.

I claim:

The ornamental design for a pair of goggles, substantially as shown and described.
